STEAMING AND PRESSING IRON

Samuel Dowinsky, New York, N. Y.

Application March 21, 1944, Serial No. 527,401

4 Claims. (Cl. 38-77)

1

This invention relates to a steaming and pressing device for ironing various materials in which the material may be dampened and pressed in one and the same operation and flow of vapor is controlled, as well as the degree of heat used, in heating the device and in generating the steam for the ironing operation.

In accordance with this invention a steaming and pressing iron is produced having the following attributes. The device embodies improvements in construction whereby to attain the proper thermal efficiency for generating water into steam or vapor without leakage, ready and in the desired moist condition at all times, and especially when starting ironing operations. The iron will be of such design that it may be manually operated with comparative ease. Due to the structural features the iron may be manufactured economically and the parts thereof may be readily assembled to produce the device and such parts also may be easily disassembled and reassembled for the maintenance of the iron in the proper working condition.

With the foregoing and other objects in view the invention will be understood from the following specification read in conjunction with the accompanying drawing, in which—

Fig. 1 is a side view of a steaming and pressing iron shown partly in longitudinal section and embodying the features of the present invention.

Fig. 2 is a sectional view taken approximately on the line 2—2 of Fig. 1.

Fig. 3 is a sectional view taken approximately on the line 3—3 of Fig. 1, certain parts of the iron are omitted.

Fig. 4 is a sectional view taken on the line 4—4 of Fig. 1.

Fig. 5 is a sectional view taken approximately on the line 5—5 of Fig. 1.

Fig. 6 is a diagrammatic view illustrating the various water and steam generating passages, steam expansion chamber and distributing passages together with the control valve means, it being understood that of the connections and the relative disposition of the features are exaggerated due to the nature of the illustration.

Referring now more particularly to the drawings, it will be apparent there is shown a manually operable steaming and pressing iron 10 including a weighted or metal body 11 comprising a base or steaming and pressing section 12, an intermediate upper water intake and steam generating section 13, and a top enclosing section 14. The sections 12, 13 and 14 are held in as-

2

sembled body forming relation by screw bolts 15. The sections 12 and 13 are heated by means of an electric heating element 16 of any suitable type, the heating element being disposed between the sections 12 and 13. The sections 12, 13 and 14 are of the usual shape; straight at the rear with curved sides converging to a point at the front.

Water enters a preheating coil 17 of tubing 10 connected with a nipple 18 by a flow coupling 19, the top section 14 having an opening therein to accommodate the coupling. The nipple 18 is integral with the section 13 and communicates with a tortuous conduit means or passage 20 formed in the section 13 in any suitable manner. In the present instance this is done by drilling and plugging as a practical way in which to obtain a long and continuous passage in which the water is initially subjected to heat by conduction to generate it into steam or vapor. The passage 20 consists of four interconnected V-shape branches 21, 22, 23 and 24, respectively. The branches 21 and 22 are of substantial size, and the branches 23 and 24 are also of substantially the same size, but they are smaller than the branches 21 and 22 and lie within the latter. The branches 21 and 23 lie in a plane above the plane of the branches 22 and 24. The flow path of the water or steam as the case may be, is 20 through the branches 21, 22, 23 and 24 in the order mentioned, and as indicated by the arrows in Fig. 6.

The passage 20 communicates with a conduit means or passage 25 formed in the base section 12 in the manner explained hereinabove, and said passage 25 constitutes a secondary steam generating means which derives heat by conduction from the heating element 16. The passage 25 consists of two interconnected V-shape branches 26 and 27, respectively, one lying within the other and both in the same plane. The outlet end of the passage 20 is connected with the inlet end of the passage 25 by an external flow coupling 28 at the rear of the body 11, there being an L-shape tubular fitting 29 carried by the section 13 communicating with the outlet end of the passage 20, and a nipple 30 on the section 12 communicating with the inlet end of the passage 25, the coupling 28 being connected with said fitting 29 and the nipple 30 as shown in Figs. 2 and 3.

The base section 12 is larger than the upper section 13 and has a recess 31 in the top. The recess is similar in shape to that of the section 13 in plan. The recess 31 accommodates the

heating element 16 and approximately the lower half of the section 13. The section 12 has an enlargement 32 at the rear extending transversely thereof, as shown in Figs. 1 to 4 inclusive. A steam expansion chamber 33 is formed in the enlargement 32 in any suitable manner, as by drilling or molding. The outlet end of the passage 25 communicates with the chamber 33 at one end by virtue of a duct 34 shown in Fig. 3. Steam entering the chamber 33 serves as a supply always ready especially when starting a pressing or ironing operation after the device has been idle. The vapor in the chamber 33 is kept in the proper moist state without being too hot due to the location of the chamber in the body 11 to the rear of the heating element 17 in spaced relation.

In order to control the flow of steam or vapor from the chamber 33, there is provided a manually operable valve 35 having an inlet 36 screwed into the enlargement 32 in communication with the interior of the chamber 33. The outlet 37 of the valve is connected with a nipple 38 by a coupling 39, and said nipple 38 is carried by the enlargement 32 in communication with a distributing passage 40 having a branch 41 in said enlargement paralleling the chamber 33, and a V-shape branch 42 in the main portion of the section 12, as shown most clearly in Figs. 4 and 6. The section 12 has a series of discharge orifices 43 therein which communicate with each of the leads of the branch passage 42 and which open through the bottom pressing face of the section 12.

The valve 35 has a lever 44 disposed adjacent a handle 45 of the iron. The handle 45 is secured in place by the bolts 45. The valve 35 is self-opening. The lever 44 may be manipulated to allow steam to flow from the chamber 33 into the passage 44 from which it flows out through the orifices 43 to the material to be steamed and pressed by the iron manipulated by the handle 45.

Water enters the coil 17 and is preheated therein as it flows through on its way into the passage 28 in the upper section 13. The passage 28 is of considerable length and causes the water to flow to and fro with respect to the point of the iron repeatedly. The water is gradually generated into vapor which passes into the passage 25 in the base section 12 where the vapor is attenuated to a desired degree before entering the expansion chamber 33 at the rear of the heated body 11. The chamber 33 serves to avoid undue pressure and keeps a supply of steam available under control of the valve 35 for delivery to the distribution passage 40. The passages 20 and 25 are so disposed as to absorb the heat conducted by the sections 12 and 13 in an effectual manner because the fluid takes a path at one level, another path nearer the heating element, then takes a path farther from the element to the passage 25 below said element in the base section 12. There can be no leakage between the sections 12 and 13 and only one exterior coupling is used to connect the passages 20 and 25. The construction, arrangement and functions of the parts lend themselves to the economic production of irons and also make it possible for each iron to be kept in the proper working condition.

I claim:

1. In a steaming and pressing iron, a body having a base section and an upper section, said base section having a bottom pressing face, said base section having a recess in the top and an enlarged portion extending transversely at its rear, said upper section fitting in the recess in the base section, heating means in the recess between said sections to heat the same, a steam chamber in said enlarged portion of the base section to the rear of said heating means in spaced relation, and inter-communicating passages leading from said steam chamber and extending in said base section and opening through said pressing face.

2. In a steaming and pressing iron, a heating element, a base section heated by said element and having a bottom pressing face and a steam expansion chamber extending transversely thereof to the rear of said element in spaced relation, a valve mounted on the base section and in direct communication with said chamber, a distributing passage in said base section having outlet orifices opening through said pressing face and an inlet at the rear of the base section, and coupling means establishing steam connection between the outlet of the valve and said inlet.

3. In a steaming and pressing iron, a heating element, a base section heated by said element and having a bottom pressing face, a steam expansion chamber formed in the base section thereof to the rear of said element in spaced relation, a tortuous steam generating passage formed in said base section and leading into said chamber, a steam distributing passage formed in said base section and having steam outlet orifices opening through said pressing face, and valve means mounted on said base section in communication with said expansion chamber and the distributing passage for controlling the flow of steam from said chamber to said distributing passage.

4. In a device for pressing material, a steaming and pressing section having a bottom pressing face, a heating element which heats said section, said section having a steam chamber formed therein and extending transversely thereof to the rear of said element in spaced relation, a steam distributing passage having outlet orifices opening through said pressing face, and valve means connected with said chamber and distributing passage to control the flow of steam from said chamber to said passage.
